Patented Mar. 11, 1913.

UNITED STATES PATENT OFFICE.

JOHN SCOTT, OF MILWAUKEE, WISCONSIN.

GAS-FIXTURE ATTACHMENT.

1,055,422.

Specification of Letters Patent.

Patented Mar. 11, 1913.

Application filed December 26, 1912. Serial No. 738,732.

To all whom it may concern:

Be it known that I, JOHN SCOTT, a citizen of the United States, and resident of Milwaukee, in the county of Milwaukee and 5 State of Wisconsin, have invented certain new and useful Improvements in Gas-Fixture Attachments; and I do hereby declare that the following is a full, clear, and exact description thereof.

10 My invention consists in what is herein particularly set forth with reference to the accompanying drawings and pointed out in the claims of this specification, its object being to provide simple, economical gas- 15 fixture attachments designed for the support of hair-curling irons while heating the same and when not in use, the employment of said supports serving to facilitate the heating of said irons and to prevent smut- 20 ting of the same.

Figure 1 of the drawings represents a side elevation of an attachment in accordance with my invention applied to a gas-fixture and supporting a hair-curling iron 25 in position to be heated, and by dotted lines a pivotal sleeve portion of the attachment is shown swung back out of the way of the gas-flame; Fig. 2, a sectional view on the plane indicated by line 2—2 in Fig. 1, and 30 Fig. 3, a perspective view of a spring-wire bracket member of said attachment.

Referring by numerals to the drawings 4 indicates the burner-end of a gas-fixture to which an attachment in accordance with 35 my invention is applicable. The bracket-member of the attachment is a single piece of suitably bent spring-wire, preferably brass, the bending of the wire being such as to form a lower circular loop 5, crossed 40 horizontal stretches 6, 7, a vertical stem 8, an upper loop 9 and a pivot 10 crossing the upper loop central of the same. The upper loop is downwardly bent in opposite directions from the stem 8, and its depressed ends 45 may be angular, as herein shown, or semi-circular as may be most convenient or desirable in practice. Another member of the attachment is a tube 11, the same being apertured adjacent to one end thereof for 50 the engagement of the pivot 10 aforesaid. The tube has play within the upper bracket-loop 9, and rests upon one or the other end of said loop when in horizontal position.

By pressing upon the stretches 6, 7, of the 55 spring-wire bracket, the loop 5 is expanded

so as to permit of its being slipped down on the burner of a gas-fixture, and the pressure being removed, the contraction of said loop serves to effect a grip of the same on said burner, whereby said bracket is supported in working position. The tube 11 being swung into the position shown by full lines in Fig. 1, it will be in the zone of the blue-flame of the lighted burner for the engagement of the hair-curling iron to 60 be heated, such an iron 12 in said tube being shown in said Fig. 1. The iron being within the tube, it cannot become smutted from the gas-flame and is therefore ready 65 for immediate use as soon as withdrawn 70 from said tube, no wiping off being necessary. It has also been demonstrated that the iron will heat more rapidly in the tube than if it be held directly in the flame, whereby a saving in gas-consumption is ef- 75 fected, and the time of the person using said iron may be utilized for other purposes while said iron is left in said tube during the heating operation. To clear the gas- 80 flame the tube may be swung into the position shown by dotted lines in Fig. 1, and the curling-iron may be left in said tube if desired. It has also been demonstrated that if the tube be of brass it will not become 85 smutted by contact with a gas-flame. Hence 90 it requires little if any cleaning, and the attachment as a whole may be readily carried about from place to place with a curling-iron, thus making it a convenient toilet 95 accessory.

While I have shown a preferred form of gas-fixture attachment, for the purpose specified, various changes in matters of detail may be made without departure from my invention as herein claimed.

I claim:

1. An attachment comprising a single piece of spring-wire bent to form a lower horizontal clamping-loop, a vertical stem, an upper loop, and a pivot crossing the upper loop, together with a tube on the pivot to have support in said upper loop of the bracket in the zone of the flame of a lighted burner of a gas-fixture caught in the clamp-loop of said bracket.

2. An attachment comprising a single piece of spring-wire bent to form a lower horizontal clamping-loop, a vertical stem, an upper loop, and a pivot crossing the loop central of the same, together with a tube on

the pivot to have support upon either terminal of said upper loop of the bracket to be in or out of the zone of the flame of a lighted burner of a gas-fixture caught in 5 the clamp-loop of said bracket.

In testimony that I claim the foregoing I have hereunto set my hand at Milwaukee

in the county of Milwaukee and State of Wisconsin in the presence of two witnesses.

JOHN SCOTT.

Witnesses:

N. E. OLIPHANT,
M. E. DOWNEY.
